J. GIBSON

CATTLE GUARD

Filed Dec. 27, 1923

FIG. 2.

FIG. 3.

INVENTOR

J. Gibson.

By *Ralph Burch*
his Attorney

UNITED STATES PATENT OFFICE.

JOSEPH GIBSON, OF DIAMOND CITY, ALBERTA, CANADA.

CATTLE GUARD.

Application filed December 27, 1923. Serial No. 683,007.

To all whom it may concern:

Be it known that I, JOSEPH GIBSON, a citizen of the Dominion of Canada, residing at Diamond City, in the county of Lethbridge and Province of Alberta, Canada, have invented certain new and useful Improvements in Cattle Guards, of which the following is a specification.

My present invention relates to improvements in cattle guards and has for its principal object the provision of a simple, cheap and easily constructed cattle guard for use in connection with railroads and the like, for preventing the passage of cattle where such is necessary or desired.

A further object is the provision of such a device which will not interfere with the passage of trains or the like but will foil the attempts of an animal to cross without seriously punishing or doing injury to the animal.

To the accomplishment of these and related objects, my invention resides in the construction, combination and arrangement of the various cooperating elements as shall be hereinafter more fully described, illustrated in the accompanying drawings and pointed out in the claims hereunto appended.

In the drawings, forming a part of this specification, wherein like characters of reference designate like parts throughout the several views,

Figure 1 is a plan of a portion of conventional railroad track illustrating the application and preferred embodiment of my invention,

Figure 2 is a transverse section taken on the line 2—2 of Figure 1, and

Figure 3 is a longitudinal section of one of the rollers illustrating a possible form of mounting.

Positioned between and transversely of the track designated by the numeral 6, I provide a pair of spaced supports 4 having turned ends 5 disposed at right angles to the body portion, said angle ends being adapted for connection to the rails. Suitable bolts or rivets 7 are used for effecting such connection and washers or other spacers not illustrated may be employed if found necessary in practice.

A corresponding and regular longitudinal series of perforations 8, in these transverse supports 4 are adapted to receive the spindles 9 of square or other suitably shaped bars 10 laid parallel with the track 6. These

bars will be of any suitable length and are carried by the spaced, transversely-disposed supporters 4 adapted to receive their spindled ends. In Figure 3 I have illustrated a possible construction for the spindle bearing ends of the rollers wherein the pintle-like axle 9 extends but a short distance exterior to the roller 10 and is inserted deeply therein. A suitable sleeve or collar 11 which may be provided with an inturned annular flange, not shown, is received by the end of the roller to substantially strengthen the same. Washers may be carried by the spindles between the ends of the rollers and the transverse support.

To relieve any undue strain such as would result from unnecessary space allowed between the ends of the rollers 10 and the transverse support 4 my invention provides for a subsequent adjustment of the distance between such transverse supports 4. This may be in the form of elongated perforations in the inturned ends 5 adapted for the reception of the securing means 7.

It will be obvious that while it may not be found advisable to provide means for adjustably spacing the parallel rollers 10 which will preferably be square in cross section, they may be spaced either to allow of or refuse the reception of an animal's hoof, as found best in practice.

While I have but described the construction and mounting of my device for positioning between the tracks, it will be apparent that the same design and arrangement will be equally applicable to location exterior to the tracks with the provision of suitable means for mounting the remote ends of the transverse supports 4. It will further be obvious that those sets of rollers which may be of any desired length can also be provided in any suitable number of sets placed successively one after another.

As many changes could be made in the above description and many apparently widely different embodiments of my invention constructed within the scope of the appended claims without departing from the spirit or scope thereof, it is intended that all matters contained in the accompanying specification and drawings shall be interpreted as illustrative and not in a limited sense.

What I claim as new and desire to secure by Letters Patent is:—

1. The combination with railroad tracks

- or the like, of a device of the character described comprising a pair of spaced supporting members disposed transversely of the tracks, having perforated, offset ends disposed at right angles to the body portion and lying parallel with said rails; securing means adapted to pass through the perforations in said ends and registering apertures in said rails; said supporting members each
- 10 having a regular and corresponding, longitudinal series of perforations; a plurality of rollers disposed parallel to said tracks; spindles mounted in the ends thereof adapted to be rotatably carried by the perforations in
- 15 said transverse supports and sleeves received by the ends of said rollers.

2. The combination with railroad tracks or the like, of a device of the character de-

scribed comprising a pair of spaced supporting members disposed transversely of the tracks, having offset ends disposed at right angles to the body portion and lying parallel with said rails; elongated perforations located in said offset ends; securing means adapted to pass through such perforations and registering apertures in said rails; said supporting members each having a regular and corresponding, longitudinal series of perforations; a plurality of rollers disposed parallel to said tracks; spindles mounted in the ends thereof adapted to be rotatably carried by the perforations in said transverse supporting members and sleeves received by the ends of said rollers.

In testimony whereof I affix my signature.
JOSEPH GIBSON.
